ELECTRIC LIGHT

Charles W. Dake, Chicago, Ill.

Application April 23, 1931, Serial No. 532,256

16 Claims. (Cl. 176—31)

This invention relates to an electric light bulb, particularly to one which may be screwed into position in a fixture and which becomes automatically locked therein so that it can not be removed therefrom.

One object of the invention is to provide in connection with such a light a construction by means of which the light, once having been locked in place, cannot be removed except upon breakage of internal parts. Another object is to provide such a light which can be removed without breaking the glass bulb but only after the breakage of internal parts, whereby the light is rendered un-serviceable for further use, but the danger of injury to an operator, either by broken glass or by an electrical current, is avoided.

Other objects will appear from time to time in the specification and claims.

My invention is illustrated more or less diagrammatically in the accompanying drawings, wherein:

Figure 1 is an elevation of the light;

Figure 2 is a cross sectional detail taken on an enlarged scale at line 2—2 of Figure 1, showing the light before it has been screwed into position;

Figure 3 is a cross sectional view, similar to Figure 2, showing the light at one stage of the operation of removal, after certain of its internal parts have been broken;

Figure 4 is a view similar to Figure 1, showing the light after the commencement of the removal;

Figure 5 is an end view of the light;

Figure 6 is a plan view of the end member of the light, seen from inside, looking in the direction of the arrow in Figure 2;

Figure 7 is an elevation with parts broken away and parts in section, showing the inner cap of the base member;

Figure 8 is a transverse sectional detail, taken at line 8—8 of Figure 3.

Like parts are designated by like characters throughout the specification and drawings.

A is a glass electric light bulb. It is formed at its upper end with an outwardly turned or extending ring A¹ and an inwardly extending core or tubular member A². Within this member A² is a glass sealing rod A³. This rod is joined to the sealing portion A⁴ of the bulb, and extends inwardly and outwardly from it. It may carry one or more arms A⁵ within the bulb which may support the filament A⁶. Suitable leads A⁷ and A⁸ are attached to the filament A⁶ and pass upwardly and outwardly through the sealing portion A⁴.

B is a threaded cap portion which is fastened

to the support by cement or any suitable fastening means B¹, and to which the lead A⁸ is fastened and with which it makes contact. At its lower end or edge the cap B is outwardly flared as at B². Above the flared portion and preferably adjacent its upper or outer end the cap B is threaded as at B³. Between the flared portion B² and the threaded portion B³ the cap is provided with one or more outwardly extending lugs B⁴. These lugs may be formed by being punched outwardly from the body of the cap B and they are preferably arranged to provide straight edges B⁵. The upper end of the cap B is open and is preferably provided with an inwardly extending flange B⁶ and one or more lugs B⁷.

C is an exterior cap member. It is inwardly bent at its lower end or edge to provide a flange C¹ which engages the under surfaces of the lugs B⁴ of the member B to prevent the member B and the bulb to which it is attached from falling out. The cap C is threaded as at C² and is provided with an inwardly extending flange C³. One or more lugs C⁴ are inwardly bent from the barrel of the cap C. For some purposes instead of the lugs, indentations might be substituted. These lugs or indentations co-operate with the lugs B⁴ of the member B in a manner which will be described below. Extending inwardly from the member C is a portion C⁵ which is preferably of such size and shape as to be relatively easily broken.

D is a plug or cap closing member formed of any suitable insulating member. It is preferably provided with a perforation D¹ which extends through it and flares outwardly adjacent its inner end. At its upper end the perforation D¹ is reduced as at D². One or more notches D³ are formed in the sides of the member D. The sides of the member are preferably inwardly and downwardly inclined as shown in Figures 2 and 3 for a portion of their height and are then given a reverse inclination throughout another portion of their height. A cavity or pocket D⁴ is formed in the inner or under surface of the plug D and a second cavity or pocket D⁵ is formed, this cavity being placed over the cavity D⁴ and the two being joined by a perforation D⁶. D⁷ is a rivet or fastening member positioned in the perforation D⁶ and engaging the breaking member C⁵ to hold it in fixed relation with the plug D. D⁸ is a contact member provided with a spring portion D⁹. This contact member is fastened in the reduced perforation D² by a rivet D¹⁰, to which the lead A⁷ is connected.

It will be realized that whereas I have here-

110

with shown and described a practical operative device, nevertheless many changes might be made in the size, shape, number and disposition of parts without departing from the spirit of 5 my invention and I wish, therefore, that my showing be taken as in a sense diagrammatic.

The use and operation of my invention are as follows:

The parts are initially assembled as shown in 10 Figures 1 and 2. In that position the plug D is held to the cap C by the breaking member C⁵ which is, of course, not yet broken. One or more of the lugs B⁷ extends into one or more of the depressions or cavities D³. The light will 15 thus move as a unit and may be screwed into place in the usual manner in a socket or fitting provided for it. When this has been done and when the light is properly seated, an added turn is given. This turn breaks the member C⁵ and thereafter the bulb may be rotated but will not 20 rotate the outer cap C because with the breaking link C⁵ broken, the inner cap B will turn in the outer cap C and the latter, therefore, cannot be unscrewed.

25 When the light is to be removed, the bulb is pressed upwardly toward the position shown in Figures 3 and 4 and until the threaded portion of the cap B engages the threaded portion of the cap C. Then further rotation of the bulb in the proper direction will cause the threads to co-operate to move the bulb upwardly or inwardly into the position shown in Figure 3. As this position is approached, the upper end of the glass member A³ contacts the plug member D. The perforation D¹ through the latter is 30 so positioned that the member A³ will inevitably contact the member D. Further inward movement of the bulb as a whole forces the member A³ against the member D and breaks it, sometimes breaking the entire interior glass structure 35 so that the members A² and A³ are broken and thus the light is rendered useless as the seal is destroyed. As the inner cap B moves into the position shown in Figure 3, the lugs B⁴ of that 40 cap engage the lugs or depressions C⁴ of the cap C, as indicated in Figures 3 and 8, and then the two caps are locked together and the bulb as a whole may be rotated in the reverse direction and removed. It will be noticed that as the 45 bulb is moved from the position shown in Figure 2 to that shown in Figure 3, the lugs B⁷ of the cap B are bent into the position shown in Figure 3 and that they move thus into the depressions D³ and in effect are locked in them and also the lugs B⁴ move to engage the lugs C⁴, 50 and thus the cap B is locked to the cap C and also to the plug D.

The bulb is shown in Figure 1 in the position of use. In Figure 4 it is shown after it has been collapsed, that is to say, after it has 55 been moved so that the inner glass member has been broken. As shown, the member A³ is broken off. Sometimes the breaking movement breaks the entire inner structure, sometimes merely a part of it, but always, before the parts have moved sufficiently together to cause locking of the two caps so that removal may take place, some part of the interior glass structure has been broken.

I claim:

70 1. In combination in an electric light, a bulb comprising a movable envelope portion and an auxiliary portion integral with it, a cap secured to said bulb and surrounding said auxiliary portion, and an anvil portion within said cap against which said auxiliary portion may be moved for fracturing said auxiliary portion, while retaining said envelope portion intact.

2. In combination in an electric light, a bulb comprising a movable envelope portion and an auxiliary portion integral with and extending beyond it, a cap secured to said bulb and surrounding said auxiliary portion, and an anvil portion within said cap against which said auxiliary portion may be moved for fracturing said auxiliary portion, while retaining said envelope portion intact. 80

3. In combination in an electric light, a bulb comprising an envelope portion and an auxiliary portion integral with it, a cap secured to said bulb and surrounding said auxiliary portion, and an anvil portion within said cap against which said auxiliary portion may be moved for fracturing said auxiliary portion, while retaining said envelope portion intact. 85

4. In combination in an electric light, a bulb comprising an envelope portion and an auxiliary portion integral with and extending beyond it, a cap secured to said bulb and surrounding said auxiliary portion, and an anvil portion within said cap against which said auxiliary portion may be moved for fracturing said auxiliary portion, while retaining said envelope portion intact, said anvil portion adapted to move with relation to said cap, said cap 90 being positioned in part about said anvil portion.

5. In combination in an electric light, a bulb comprising an envelope portion and an auxiliary portion integral with and extending beyond it, a cap secured to said bulb and surrounding said auxiliary portion, and an anvil portion within said cap against which said auxiliary portion may be moved for fracturing said auxiliary portion, while retaining said envelope portion intact, said anvil portion adapted to move with relation to said cap, said cap 100 being positioned in part about said anvil portion.

6. In combination in an electric light, a sealed glass bulb, said bulb comprising a main envelope portion and an additional portion, formed integral therewith, a cap fixed to said bulb, a second cap surrounding said first cap, and a breakable member adapted when unbroken to co-operate to hold the two against relative movement, whereby the light as a whole may be moved as a 110 unit, the two caps free for relative movement when the breakable member is broken the two caps threadedly engaging each other, whereby rotation of the bulb will not accomplish removal of the light as a whole, and means operative in 120 response to rotation of the bulb in one direction, for relocking the two caps together.

7. In combination in an electric light, a sealed glass bulb, said bulb comprising a main envelope portion and an additional portion, formed integral 125 therewith, a cap fixed to said bulb, a second cap surrounding said first cap and carrying an anvil portion, and a breakable member adapted when unbroken to co-operate to hold the two against relative movement, whereby the light as a whole 130 may be moved as a unit, the two caps free for relative movement when the breakable member is broken, whereby rotation of the bulb will not accomplish removal of the light as a whole, and means operative in response to rotation of the 135 bulb in one direction, for relocking the two caps together, the clearance within the first cap such that the two caps do not become locked together until the additional portion of the bulb has been fractured. 140

8. In combination in an electric light bulb, comprising a main envelope portion and an additional portion, means for preventing the removal of the bulb from a socket, said means including a cap secured to said bulb, a second cap about 145 said first cap, and adapted to engage a socket, there being a clearance within the caps and within the first cap such that when the two caps are moved together the additional portion of the glass bulb is broken. 150

8. In combination in an electric light bulb, means for preventing the removal of the bulb from a socket, said means including a threaded cap secured to said bulb, a second cap about said first cap, and adapted to engage a socket, threaded portions on said caps adapted to be engaged and to be drawn together, there being a clearance within the caps and within the first cap such that as the two caps are moved together an interior portion of the glass bulb is broken. 80
9. In combination in an electric light bulb, means for preventing the removal of the bulb from a socket, said means including a cap secured to said bulb, a second cap about said first cap, and adapted to engage a socket, the caps being free for relative movement when the light is seated in the socket, there being a clearance within the caps and within the first cap such that when the two caps are moved together an interior portion of the glass bulb is broken, and means effective after a predetermined movement of the first cap to lock the caps together. 85
10. In combination in an electric light bulb, a glass bulb having a projection extending beyond its boundaries, a cap fixed to said bulb and provided with engaging means, a second cap surrounding said first cap, the caps being free for relative movement when the bulb is in use, means on the caps, effective when they are given relative rotation, to draw them progressively together, there being a clearance within the caps and about said projection such that the latter will be broken before the two caps have reached the limit of their movement toward each other. 90
11. In combination in an electric light bulb, a glass bulb having an integral additional portion, a cap fixed to said bulb and provided with engaging means, a second cap surrounding said first cap, the caps being free for relative movement when the bulb is in use, means on the caps effective when they are given relative rotation to draw them progressively together, and means for locking them together after a predetermined amount of such rotational movement has occurred, the clearance within the caps and about said integral additional portion such that the latter will be broken before the two caps have reached the limit of their movement toward each other. 95
12. In an electric light, a glass bulb formed with an internal portion, a cap fixed to said bulb, provided with a threaded end and with outwardly projecting lug members, a second cap positioned about said first cap, threaded and provided with inwardly extending lugs, the two caps being free for rotational and longitudinal movement when in use, the threads of the first cap adapted to be engaged with the threads of the second cap when the two are telescoped together, there being a clearance within the caps and between the parts such that upon a predetermined movement together of the two caps, the internal portion is fractured. 100
13. In an electric light, a glass bulb formed with an internal portion, a cap fixed to said bulb, provided with outwardly projecting lug members, a second cap positioned about said first cap, and provided with inwardly extending lugs, the two caps being free for longitudinal movement when the light is in use, the lugs of the first cap adapted to be engaged with the lugs of the second cap when the two are telescoped together, the clearance between the parts being such that upon a predetermined movement together of the two caps, the internal portion is fractured, the lugs on the said caps adapted to lock them together when moved into opposition with each other. 105
14. In an electric light, a glass bulb, comprising a main envelope portion and having an auxiliary portion, a cap secured to said bulb and surrounding said auxiliary portion, a second cap surrounding said first cap, the two caps so shaped that they may be given initial relative movement in one direction and provided with engaging members which, after a predetermined relative rotation, cause engagement of the two caps to lock them together for unitary rotation in the reverse direction, there being a plug mounted in the second cap, there being a clearance within the caps and between the plug and the auxiliary portion of the bulb such that when the caps are drawn together the auxiliary portion of the bulb is fractured. 110
15. In combination in an electric light bulb, comprising an envelope portion and an auxiliary portion integral with it, a cap secured to said bulb and surrounding said auxiliary portion, and a second cap mounted about the first cap, the two caps joined by a link which is broken when the light is put into use, the two caps being adapted, after the light has been put in use, to have relative longitudinal movement, and means for locking the caps together, said locking means acting to lock the caps together in response to relative telescoping movement of the caps, said telescoping movement being effective to fracture the auxiliary portion of the bulb. 115
16. In combination in an electric light bulb, comprising an envelope portion and an auxiliary portion integral with it, a cap secured to said bulb and surrounding said auxiliary portion, and a second cap mounted about the first cap, the two caps joined by a link which is broken when the light is put into use, the two caps being adapted, after the light has been put in use, to have relative movement, and means for locking the caps together, said locking means acting to lock the caps together in response to relative movement of the caps, said relative movement being effective to fracture the auxiliary portion of the bulb. 120
